UNITED STATES PATENT OFFICE.

WILLIAM N. OEHM AND GOMERT POWELL, OF MICHIGAN CITY, INDIANA.

NAILING MACHINE.

1,393,816.

Specification of Letters Patent.

Patented Oct. 18, 1921.

Application filed December 2, 1920. Serial No. 427,821.

To all whom it may concern:

Be it known that we, WILLIAM N. OEHM and GOMERT POWELL, citizens of the United States and Holland, respectively, and residents of Michigan City, county of Laporte, and State of Indiana, have jointly invented certain new and useful Improvements in Nailing-Machines, of which the following is a specification and which are illustrated in the accompanying drawings, forming a part thereof.

The invention relates to a nailing machine including a pneumatic hammer and adapted especially for driving the nails in floor boards, particularly the flooring of cars.

The objects of the invention are to provide for the ready shifting of the machine and permanently positioning it for driving a nail; to provide a simple and efficient nail-feeding device, and to secure rapidity of operation.

An embodiment of the invention is illustrated in the accompanying drawings, in which—

25 Figure 1 is a longitudinal section of the machine, partly in elevation, on the line 1—1 of Fig. 2;

Fig. 2 is a side elevation of the machine;

30 Fig. 3 is a plan section on the line 3—3 of Fig. 1;

Fig. 4 is a sectional view on the line 4—4 of Fig. 3;

Fig. 5 is a detail section on the line 5—5 of Fig. 3; and

35 Fig. 6 is a detail section on the line 6—6 of Fig. 4.

The machine comprises a pneumatic hammer, conventionally shown at 10, and which may be of any desired construction having 40 the usual handle 11 and controlling valve 12. This hammer telescopically enters a tube 13, the lower end 14 of which is contracted to form a nipple and positioned in this nipple is a bushing provided with spurs 45 15 which will engage the board into which the nail is to be driven and hold the machine in proper position.

A pedal 16, adapted to have its outer end loosely rest upon the floor, is connected by 50 means of links 17, 18, to a pair of pull rods 19, 20, attached to the upper end of the hammer casing, and a spring 21, coiled about one of the rods, as 19, and reacting between the upper end thereof and a guide bracket 22 55 attached to the tube 13, normally holds the hammer in elevated position.

A feed tube 23 enters the tube 13 laterally for delivering nails thereto, and which are fed through the feed tube from a suitable receptacle, such as a funnel 24, connected therewith by means of a tube 25. The size of the tube 25 is such that the nails pass through singly, and as each nail descends it is arrested at the upper end of the tube 23 by a pivoted dog 26 projecting into its path 60 a sufficient distance to certainly engage its head. This dog is held in nail-engaging position by means of a spring 27.

A trip arm 28 is pivoted at 29 to an arm 30 secured to the pivot of the dog 26, and 70 projects into the path of a trip 31 carried by one of the pull rods, as 20. As the hammer is moved upwardly by the action of the spring 21 the trip 31 engages below the arm 28 and turns the dog 26, releasing the nail X 75 and permitting it to drop into the tube 13. As the hammer is drawn down the trip 31 passes the trip arm 28, turning it on its pivot, and this latter arm is immediately returned to its normal position by the action of 80 a spring 32.

Within the lower contracted end 14 of the tube 13 there is slidably fitted a bushing 33, the bore of which is suitable to allow the passage of a nail therethrough while holding 85 it in upright position. The downward movement of the bushing 33 is limited by a screw stud 34, projecting through a longitudinal slot in the tube section 14. As the machine is positioned for the driving of a nail the 90 bushing 33 is moved upwardly a short distance by its engagement with the floor and insures the entry thereinto of the nail now within the body portion of the tube 13.

A punch or nail set 35, forming an element of the pneumatic hammer, is positioned to bear upon the nail when the latter occupies the bushing 33, and to drive it as the hammer is operated. The nail set 35 has a limited longitudinal movement within the 100 lower end of the barrel of the hammer to permit the latter to be advanced after each blow is struck.

The operation of the device, as will be understood from the foregoing description, 105 is as follows:—

Assuming that the feed tube 25 is filled with spikes, and that one has been driven, the machine rests on the spot, the operator standing with one foot on the pedal 16 and 110 the other on the floor. He now takes a step forward, keeping one foot on the pedal, and

then lifts the machine to the new position, at the same time releasing slightly the pressure on the pedal so as to permit the springs 21, 21, to raise the hammer and thus release 5 a spike, which drops obliquely into the tube 13. During the forward movement the free end of the hinged pedal is permitted to drag along the floor. At the new position the machine is dropped in place, and is there 10 held against accidental removal by the claws 15, the bushing 35 being forced upwardly relative to the tube 14, thus straightening the spike so that it is ready to be driven into the floor.

15 The operator now presses the lever of the air controlling valve 12 with his thumb, and at the same time steps on the pedal 16, thus lowering the hammer and pressing the set 20 into contact with the spike. The set is allowed a small amount of play within the 25 hammer barrel because of the recess 36, and the head of the spike may therefore be driven by the air pressure slightly below the level of the floor without injury to the hammer.

The pressure on the pedal is released, and another spike is automatically dropped into the tube 13 on the upward movement of the hammer. The operator again moves the 30 machine to a position slightly in advance of the last one and then drops the machine in place, keeping his foot always on the pedal 16. It is found that by the use of this machine very rapid nailing can be accomplished, and it is of particular value in nail-

ing the flooring of cars, where heavy spikes are used and rapid operation is essential. The device is a unitary structure, all of whose parts combine in rendering the whole 40 efficient.

We claim as our invention—

1. In a nailing machine, in combination, a nail-positioning nipple, a bushing slidable within the nipple and so constructed as to 45 straighten the nail.

2. In a nail box, in combination, a nail-positioning nipple, and a bushing longitudinally slidable therein.

3. In a nailing machine, in combination, a nail-receiving chamber, nail-feeding means 50 opening obliquely into said chamber at one side thereof, a nail-positioning nipple of less diameter than the chamber located below the same, and a longitudinally slidable bushing within the nipple.

4. A nail box comprising, in combination, a nail-receiving chamber tapered at its lower end, a nail-positioning nipple of less diameter than the receiving chamber located below the same, and a longitudinally slidable bushing within the nipple having its upper end internally tapered to correspond to the taper of the receiving chamber.

5. In a nailing machine, in combination, a nail box, a nipple leading from the bottom 60 of the box, and a slidable bushing within the nipple and normally projecting beyond its outer end.

WILLIAM N. OEHM.
GOMERT POWELL.
